(57) **CLAIM**

The ornamental design for a housing for a sleep enhancement diffuser device, as shown and described.

DESCRIPTION

FIG. 1 is a perspective view of the left, front, and top of a housing for a sleep enhancement diffuser device, showing my new design.

FIG. 2 is a front view of the housing for a sleep enhancement diffuser device of FIG. 1.

FIG. 3 is a back view of the housing for a sleep enhancement diffuser device of FIG. 1.

FIG. 4 is a left side view of the housing for a sleep enhancement diffuser device of FIG. 1.

FIG. 5 is a right side view of the housing for a sleep enhancement diffuser device of FIG. 1.

FIG. 6 is a top view of the sleep housing for a sleep enhancement diffuser device of FIG. 1; and,

FIG. 7 is a bottom view of the sleep housing for a sleep enhancement diffuser device of FIG. 1.

Portions or features of the housing for a sleep enhancement diffuser device not shown in the drawings form no part of the claimed design. The broken lines in the drawings showing portions of the housing for a sleep enhancement diffuser device form no part of the claimed design.

1 Claim, 7 Drawing Sheets
